UNITED STATES PATENT OFFICE.

CHARLES WELHART, OF LOWELL, AND GEORGE R. TOWNSEND, OF WINCHESTER, MASSACHUSETTS, ASSIGNEES, BY MESNE ASSIGNMENTS, TO EDEN WASHER CORPORATION, A CORPORATION OF DELAWARE.

RELEASEABLE BALANCED-PRESSURE WRINGER.

Application filed October 2, 1919. Serial No. 327,972.

To all whom it may concern:

Be it known that we, CHARLES WELHART and GEORGE R. TOWNSEND, citizens of the United States, and residents of the city of Lowell and town of Winchester, respectively, in the county of Middlesex and State of Massachusetts, have invented certain new and useful Improvements in a Releasable Balanced-Pressure Wringer; and we do hereby declare that the following is a full, clear, and exact description of the same, reference being had to the accompanying drawings and to the numerals of reference marked thereon, which form a part of this specification.

This invention relates to that class of wringers shown in our co-pending application Serial No. 327,971, filed Oct. 2, 1919, for "Balanced pressure wringer".

In these types of wringers the springs which maintain the wringer rolls in yieldable contact with one another are horizontally disposed in the upper transverse frame member of the wringer and exert a pressure upon the bearings for the upper wringer roll through bell-crank arms, and said springs bear against a floating plate disposed therebetween whereby the pressure effect of the springs is equalized and by retraction of the floating plate the stress on the springs is immediately released to permit separation of the wringer rolls.

Furthermore, this invention contemplates the use of assembly pins for retaining the upper casing structure of the wringer on the uprights and said pins are quickly detachable for disassembly of the wringer. Furthermore, detachment of the upper casing of the wringer is designed to release the gear-casing cover whereby access is gained to the intermeshing gears of the wringer rolls.

It is an object therefore of this invention to construct a wringer having a quickly detachable upper transverse casing frame member which serves to retain the gear-casing cover in place and which contains resilient means for transmission of pressure through interior cranks to the bearings for the upper wringer roll and with resilient means provided with a quick-releasing mechanism to relieve the same of stress and also to operate as an equalizing device to equalize the pressure effect transmitted to the wringer-roll bearings.

It is also an object of this invention to provide a quickly releasable balanced pressure wringer with mechanism permitting quick detachment of the upper housing portion of the wringer mechanisms which by release and detachment permits ready removal of the wringer rolls and also permits detachment of the gear-casing cover for the wringer-roll gears.

Other and further important objects of this invention will be apparent from the disclosures in the drawings and specification.

The invention in a preferred form is illustrated in the drawings and hereinafter more fully described.

Drawings.

Figure 1 is an elevation of a wringer embodying the principles of our invention with a portion of the driving mechanism therefor of a washing machine shown fragmentarily.

Figure 2 is an end elevation of the wringer.

Figure 3 is a central, vertical, longitudinal section taken through the wringer with parts in elevation.

Figure 4 is an elevation partly broken away showing the relation of the wringer springs.

Figure 5 is a top plan view of the wringer.

Figure 6 is a detail section on line 6—6 of Figure 1.

Figure 7 is a detail section, with parts omitted, on line 7—7 of Figure 1.

Figure 8 is a fragmentary section on line 8—8 of Figure 1.

Description.

The wringer comprises a base 1 which may have a gear casing 2 integral therewith provided with a detachable cover 3. The gear casing portion 2 affords a frame structure by which the wringer is attached to and supported upon a casing frame structure 4 in which the driving mechanisms for the wringer are situated. As shown, said base frame member 1 is provided with uprights 5 and 6 which may or may not be integral therewith, as desired. Each of said uprights 5 and 6 is substantially of channel section, as shown clearly in Figure 5. Engaged over the upper ends of the respective uprights 5 and 6 is a transverse upper frame member or housing 7 also of

channel section and provided with apertures for registration with corresponding apertures in the upper ends of the uprights 5 and 6 to receive engaged therethrough detachable assembly or retaining pins 8, each having a head 9 and a handle 10. Said handles 10 are pivoted to the pins 8 so that elevation of the handle to substantially horizontal position will permit the same to be withdrawn with the pins 8 outwardly through the registering apertures and release the assembled members. Said upper transverse frame member 7 is provided with longitudinal slots 11, two on each side thereof, and disposed within said member are spiral compression springs 12 each seating in one of two collars 13. Said collars 13 each have transversely extending pin or lug projections 14 extending therethrough and projecting outwardly through and beyond the slots 11. Fitted over the upper frame member 7 is a channel-shaped plate or device denoted as a whole by the reference numeral 15 and having guideways in the form of slots 16 on each side thereof each of which has an upwardly directed portion at its ends in which the outer ends of the respective pins 11 normally seat so that the collars 13 are normally held spaced apart and said plate 15 acts as an equalizing means between the springs 12, inasmuch as said plate 15 is slidable longitudinally on the member 7. The upper portion of the plate 15 is provided with an aperture with the metal flanged upwardly on the ends thereof, and pivoted therein is a handle 17 having on its lower end a rounded cam surface 18 which normally bears upon the top surface of the frame member 7, as shown in Figure 3. Movement of the handle 17 in either direction transversely of the wringer will serve to elevate the plate 15 thereby displacing the pins 14 from the offset ends of the slots 16 and permit release of the springs 12. Thus the device 15 controls the yielding springs or mechanisms in either their operative or inoperative positions.

The outer ends of each of the springs 12 bear against the collars 13 and said collars 50 rest against the respective ends of wing screws 20 which are threaded adjustably through bell cranks 21 pivoted in the frame member 7. Each of said bell cranks has a rounded portion 22 which bears upon the upper portion of a bearing 23 for the shaft of the upper wringer roll 24. A lower wringer roll 25 is provided with a shaft which rests in bearings 26 and the pressure of the upper roll 24 received through the bearings 22 serves to hold the lower wringer roll 25 seated in its bearings 26. Intermeshing pinions 27 and 28 are provided upon the shafts for the respective wringer rolls 24 and 25.

65 The frame member 7 which fits down-

wardly over the uprights 5 and 6 is cut away to form an offset 29, shown clearly in Figures 1, 3 and 4, which engages over the upper portion of the gear-casing cover 3 to hold the same in place, and the lower flat end of said cover abuts against the casing 4 so that the cover 3 cannot be removed or detached without releasing of the frame member 7 by removal of its retaining pins 8.

Operation.

The upper wringer roll 24 is held yieldably thrust against the lower wringer roll 25 and the two wringer rolls are thus held properly disposed in their bearings owing to the thrust of the respective springs 12. The thrust of the springs 12 is exerted upon the bearings 22 for the upper wringer roll 24 and is transmitted thereto through the bell cranks 21 which are provided with the adjustable, threaded wing bolts 20 to vary the stress upon the springs and consequently the pressure between the rolls. Regardless of the adjustment of the respective wing bolts 20, the stress upon the respective springs 12 is equalized owing to the fact that said springs seat against collars 13 which are slidable and are held by their pins 14 in fixed relation with the slidable or floating plate 15.

If, for any reason, a quick release of the pressure between the wringer rolls is desired to permit removal of an article from between the rolls or to permit disassembly of the wringer, it is only necessary to shift the handle 17 in either direction transversely of the wringer to elevate the floating plate 15 and thereby release the pins 14 for movement toward one another in the slots 16 of the floating plate and slots 11 of the frame member 7. With the springs in released position it is a simple matter to restore the same to stressed relation by manually moving the pins 14 back into latched relation at the ends of the respective slots 16 of the plate 15, and to facilitate such an operation the two bolts 20 may first be loosened.

Furthermore, with the springs in released condition, if it is desired to disassemble the wringer, the handles 10 are swung upwardly and out to thrust the assembly pins 8 outwardly so that the same may be withdrawn together with the handles 10, thus permitting detachment of the transverse frame member 7 with its associated mechanisms from the wringer. Detachment of the frame member 7 also releases the gear-casing cover 3 permitting a removal thereof, and, further, gives access to the wringer rolls which may be also removed with the bearings therefor.

It is obvious, therefore, that the wringer may be quickly dismantled for any purpose

whatsoever such as repair or replacement of parts and again quickly assembled. Furthermore, the horizontal arrangement of the springs for the wringer rolls reduces the size of the wringer considerably and makes a much neater appearance and one which, for compactness, is far more desirable for use on a power driven washing machine than the types heretofore used.

10 We are aware that numerous details of construction may be varied through a wide range without departing from the principles of this invention, and we therefore do not purpose limiting the patent granted otherwise than necessitated by the prior art.

Claims.

1. A wringer of the class described comprising a pair of wringer rolls, a plurality of 20 spring means mounted substantially parallel to said rolls to hold the same yieldably toward one another, a slidable equalizing means disposed between said spring means, and a latching means provided on said 25 equalizing means to latch said spring means in position to transmit pressure to the rolls.

2. A wringer of the class described comprising a pair of rolls, a plurality of resilient means maintaining the same yieldably 30 together, horizontally slidable equalizing mechanism disposed between said resilient means, and latching devices forming a part thereof to latch said mechanism to said resilient means and detachable therefrom to 35 permit release of said resilient means to unstressed position by elevation of said mechanism.

3. In a wringer of the class described a pair of rolls, a plurality of resilient means 40 to hold said rolls yieldably together, equalizing mechanism between said means, latching devices on said mechanism to positively interlock with said resilient means and permit release of said resilient means by movement substantially at right angles to the line of movement of said resilient means, and means for varying the pressure of said 45 resilient means to vary the pressure between said rolls.

50 4. In a wringer of the class described wringer rolls, a plurality of horizontally mounted spring means for holding said rolls yieldably together, a plate mounted between said spring means and having latching devices engageable with said spring means, and a lever to move said plate transversely to the line of movement of said spring means and release said spring means to permit separation of the rolls.

55 5. A wringer of the class described comprising a pair of rolls normally stressed,

a plurality of spring means mounted substantially parallel to said rolls to hold the same yieldably together, a member slidably mounted to equalize the stress between said 65 spring means, said floating member having latching devices engaging with said spring means, and mechanism for displacing said member to unlatch said spring means therefrom and relieve the same of stress.

6. A wringer frame comprising upright end members, a gear casing adjacent one of said end members, a cover for said gear casing, a longitudinal housing member fitting over said end members and locking said 75 cover in place, and means for detachably securing said longitudinal member to said end members.

7. In a wringer having a pair of rolls, one movable toward and from the other, 80 means including a plurality of longitudinally arranged springs for maintaining said rolls in operative relation, said springs having guiding abutments on their inner ends, a casing for housing and guiding said 85 springs, and a latch on said casing having a guideway and retaining notches for receiving said abutments.

8. In a wringer having a pair of rolls with one movably mounted relative to the other, 90 means including a pair of yielding elements for normally maintaining said rolls in operative relation, said elements being parallel with the rolls, a frame comprising a part of the wringer, and an equalizing device 95 slidably supported on said frame and having guideways with spaced indentures, said elements having means engageable in said indentures and releasable therefrom by a vertical movement of said device.

100 9. In a wringer, a pair of rolls mounted for relative movement, yielding means for holding said rolls in yielding engagement, a frame comprising a part of the wringer, a device slidably supported upon said frame 105 and having guideways, and said yielding means having supporting members slidable in said guideway and adapted to be held in spaced relation therein, for tensioning said yielding means, and means for elevating said device for releasing said members from their spaced relation for releasing the pressure on said rolls.

110 In testimony whereof we have hereunto subscribed our names in the presence of two 115 subscribing witnesses.
